Primary Examiner — Celia Murphy*Assistant Examiner* — Clare Ann Gannon(74) *Attorney, Agent, or Firm* — Gokalp Bayramoglu(57) **CLAIM**

The ornamental design for an anti-fatigue mat, as shown and described.

DESCRIPTION

FIG. 1 is a perspective view of the anti-fatigue mat showing my new design;

FIG. 2 is a top plan view thereof.

FIG. 3 is a bottom plan view thereof.

FIG. 4 is a front elevational view thereof.

FIG. 5 is a rear elevational view thereof; and,

FIG. 6 is a left side view thereof, the right side being a mirror image.

The broken lines shown in FIG. 3 depict portions of the anti-fatigue mat that form no part of the claimed design.
